UNITED STATES PATENT OFFICE.

EDGAR L. LOGEE, OF PROVIDENCE, RHODE ISLAND.

DESIGN FOR A LACE-PIN.

SPECIFICATION forming part of Design No. 16,718, dated June 1, 1886.

Application filed April 13, 1886. Serial No. 198,776. Term of patent 3½ years.

To all whom it may concern:

Be it known that I, EDGAR L. LOGEE, a citizen of the United States, residing at Providence, in the county of Providence and State of Rhode Island, have invented and produced a new and original Design for Jewelry, the same consisting of a Lace-Pin, of which the following is a specification, reference being had to the accompanying drawings, forming a part thereof.

Figure 1 is an elevation or face view of my said newly-designed lace pin, and Fig. 2 is a side or edge view of the same, these two figures being necessary to fully illustrate the design.

The leading feature of my design consists of a circular central jewel-setting, with a light frame on each side carrying a pointed figure at each end.

In the drawings the central jewel-setting is represented by *a*, the light open-work frame on each side with curvilinear top and bottom and a straight central bar is indicated by *b b*, and the end pieces, *c c*, with diagonal grooves, as represented in Fig. 2.

I claim—

The design for a lace-pin, consisting of a central jewel-setting, *a*, the light framed panels *b* on each side, and the end pieces, *c c*, as herein shown and described.

EDGAR L. LOGEE.
